UNITED STATES PATENT OFFICE.

OTTO WALKER, OF ZURICH, SWITZERLAND.

FIREARM.

Application filed May 21, 1924. Serial No. 714,894.

To all whom it may concern:

Be it known that I, OTTO WALKER, merchant, a citizen of the Swiss Confederation, residing at Zurich, Bleicherweg 28, Canton 5 Zurich, Switzerland, have invented new and useful Improvements in Firearms, of which the following is a specification.

The present invention relates to improvements in fire arms, especially in rifles, machine guns and so on.

The object of the invention is to reduce the noise, the recoil and the muzzle fire to a minimum without impairing the good qualities of the fire arm. I attain these objects 15 by providing slots in the barrel which slots communicate with chambers arranged around the barrel. The chambers may be formed by a sleeve surrounding the barrel and being screwed on to the barrel.

20 In the accompanying drawing one mode of construction is shown by way of an example.

Fig. 1 shows part of a barrel of a rifle in section.

25 Fig. 2 is a cross-section on line A—B of Fig. 1.

In the drawing 1 denotes the barrel of a rifle which is provided with radial slots 2. The slots 2 are arranged in rows at different 30 distances apart. The barrel 1 is surrounded by a sleeve or mantle 3 which is screwed on

to the barrel at its hind end. The sleeve 3 is divided in chambers 5 by rings 4 7 and 8 arranged between two consecutive rows of slots 2. The bore 6 of the barrel communicates by said slots 2 with the chambers 5. The sleeve 3 is fastened with one end only to the barrel 1 preferably the hind end the fore end 7 is slidable on the barrel to allow the expansion and contraction of the 40 sleeve 3.

On firing a shot the gases pass from the barrel 1 into the chambers 5 whereby the noise is minimized as well as the flare at the muzzle. The initial speed of the bullet 45 is not decreased in any perceptible manner.

What I wish to secure by U. S. Letters Patent is:

A fire arms barrel having radial slots arranged in spaced relation longitudinally of the barrel, a mantle of greater diameter than, secured on and surrounding said slotted portion of the barrel and partition rings in said mantle and through which the barrel extends, said partition rings being arranged between slots of the barrel and forming spaced chambers in said mantle, each of which chambers is in communication with one of said slots.

In witness whereof I affix my signature.

OTTO WALKER.
